UNITED STATES PATENT OFFICE.

WILLIAM WYANT CASSIDY, OF DEADWOOD, SOUTH DAKOTA.

CONDENSER.

1,203,581.

Specification of Letters Patent.

Patented Nov. 7, 1916.

Application filed August 10, 1915. Serial No. 44,714.

To all whom it may concern:

Be it known that I, WILLIAM W. CASSIDY, a citizen of the United States, and a resident of Deadwood, in the county of Lawrence and 5 State of South Dakota, have invented a new and Improved Condenser, of which the following is a full, clear, and exact description.

My invention relates to surface condensers, and has for its object the provision of a simple, inexpensive and efficient condenser having baffle plates therein so arranged as to prevent the steam entering the condenser from flowing directly to the air intake without circulating between the cooling tubes of 15 the condenser.

Referring to the accompanying drawing, my condenser is shown in a vertical section, and in which the casing 1 has a steam inlet 2 at the top thereof. The rows of cooling 20 tubes 3 are so located within the casing that there is preferably a larger space between the walls of the casing with the upper rows of tubes than between the sides of the casing and the lower rows of tubes. This space between the walls of the casing and the rows of the tube gradually decreases toward the bottom. The side walls of the casing facing the sides of the cooling tube are braced by tie rods 4 disposed at suitable intervals between the rows of tubes 3. An outlet 5 for 25 condensed water is formed in the bottom of the casing; and an air outlet 6 is provided in one side of the casing adjacent the bottom. The air outlet is disposed at right angles to 30 the cooling tubes 3.

To prevent the steam entering the casing 1 from flowing easily to the air outlet 6, baffle plates 7 are provided above and below the inlet extending between the rows of cooling 40 tubes. These baffles may extend only partially across the condenser, but their length must exceed the width of the air outlet. Baffle plates 8, extending through the entire length of the condenser, are also provided below and above the air outlet 6 to 45 prevent the steam confined between the row of tubes and the side wall, where the outlet is provided, from flowing directly to the outlet without circulating between the rows of 50 tubes. As will be seen, the baffle plates 7 and 8 are staggered. To further improve

condensation of the steam, baffle plates 9 are provided which extend the length of the casing adjacent the side walls thereof and above the level of the air outlet in the space between the 1's of cooling tubes where the tie bolt 4 is provided. These baffles 9 prevent the steam confined in the large space formed by the provision of the tie bolt from flowing directly to the air outlet without circulating about the cooling tubes.

It is self-evident that the baffle plates can be utilized within any shape of condensers, whether the steam enters at the sides or at the bottom as the baffle plates can be always so arranged as to prevent the steam entering the condenser from flowing directly to the air outlet without circulating between the cooling tubes.

I claim:

1. In a condenser of the class described, a casing having a steam inlet at the top thereof, an air outlet adjacent the bottom thereof and a condensate outlet at the bottom of the casing, tie bolts connecting the sides of the 75 casing, rows of cooling tubes disposed transversely of the tie bolts and the air outlet, baffle plates above and below the air outlet extending between the rows of tubes substantially to the middle of the casing and partially lengthwise thereof, and baffle plates above the first-mentioned baffle plates adjacent the air outlet extending through the entire length of the casing, substantially as and for the purpose set forth. 80

2. In a condenser of the class described, a casing having a steam inlet at the top an air outlet at the side adjacent the bottom and a condensate outlet at the bottom, tie bolts connecting the sides of the plates, rows of cooling tubes within the casing extending transversely of the tie bolts and the air outlet, baffle plates extending from the air outlet above and below the same between the horizontal rows of tubes substantially to the middle of the casing and partially along the casing, baffle plates above each of the first-mentioned baffle plates extending along the casing and located adjacent the air outlet, said second-mentioned baffle plates extending only to the second vertical rows of tubes from the side wall of the casing, and baffle 95

plates extending along the casing between the upper and lower rows of cooling tubes at the tie bolt which is located adjacent the air outlet, said last-mentioned baffle plates being 5 located between the vertical rows of cooling tubes adjacent the sides of the casing.

In testimony whereof I have signed my

name to this specification in the presence of two subscribing witnesses.

WILLIAM WYANT CASSIDY.
